DESIGN FOR A GAME BOARD

Theodore Nitza and Edward W. Karl,
Painesville, Ohio

Application February 15, 1941, Serial No. 99,027

Term of patent 3½ years

To all whom it may concern:

Be it known that we, Theodore Nitza and Edward W. Karl, citizens of the United States, residing at Painesville, in the county of Lake and State of Ohio, have invented a new, original, and ornamental Design for a Game Board, of which the following is a specification, reference being had to the accompanying drawing, forming part thereof.

The figure is a plan view of a game board, showing our new design. The article is of no appreciable or substantial thickness.

We claim:

The ornamental design for a game board, as shown and described.

THEODORE NITZA.
EDWARD W. KARL.
